UNITED STATES PATENT OFFICE.

MAURICE M. ANDERSON, OF MADISON, WISCONSIN.

PANTOGRAPH.

Application filed December 20, 1923. Serial No. 681,830.

To all whom it may concern:

Be it known that I, MAURICE M. ANDERSON, a citizen of the United States, residing at Madison, in the county of Dane and State 5 of Wisconsin, have invented certain new and useful Improvements in Pantographs, of which the following is a specification.

This invention relates to improvements in pantographs particularly adapted for use 10 in projecting maps, drawings, and the like.

An important object of the invention is to provide a device which will reproduce maps or the like to conform to the size and shape of the original.

15 A further object of the invention is to provide a device of this character which requires little effort to operate and is unlikely to become out of order.

20 A further object of the invention is to provide a device of this character which is comparatively simple yet durable of construction and efficient for the purpose intended.

25 Other objects and advantages of this invention will be apparent during the course of the following description.

In the accompanying drawings forming 30 a part of this specification and in which like numerals are employed to designate like parts throughout the same:

Figure 1 is a top plan view of the device secured to a drawing board.

Figure 2 is a side elevation of the same,

35 Figure 3 is a transverse sectional view taken on the line 3—3 of Figure 1, and

Figure 4 is an end elevation of the device.

In the drawings, wherein for the purpose of illustration is shown the preferred embodiment of my invention, the numeral 40 10 designates a drawing board, the size and shape thereof depending on the outline it is desired to reproduce. It is considered desirable to provide transverse braces as shown at 11 to retain this board in firm

45 condition and also to prevent warping thereof. Near one extremity of the drawing board 10 I provide a support arm 12, said support arm being positioned on the under side of the drawing board preferably adjacent the cross brace 11 which will strengthen the position thereof. In order to secure the support arm 12 to the drawing board in a rigid manner and without damaging the drawing board, a pair of plates 13 having 50 suitable apertures therein are placed on the surface of the board and a pair of thumb

screws 14 are connected therethrough with the support arm and retain same securely in position.

Pivotedly secured to the support arm 12 60 and forming a substantially rectangular frame are a pair of extension bars 15 and connecting bar 16, said connecting bar being secured to the opposite extremities of the extension bars 15 by means of thumb screws which act as pivots and permit angular movement of the bars 15 and 16 about the support arm 12.

The connecting bar 16 carries a cross 70 arm 17 which is secured to said connecting bar midway of its extremities in a fixed manner. One extremity of the cross arm 17 has a tracing arm 18 pivotally mounted thereon, said tracing arm carrying a tracer 19, in an aperture formed at the forward end thereof. The opposite end of the cross arm 17 has a transmitting arm 20 pivotally mounted thereon, the forward extremity of said transmitting arm having a pencil 21 75 or the like secured thereto. A brace 22 is pivotally connected with the central portion of the tracing arm and transmitting arm and retains said arms in parallel planes at all times.

In use, the map or other matter it is desired to trace is secured on one extremity 80 of the drawing board as illustrated at 23, while the paper or other material upon which an outline of the map or other matter is to be traced, is positioned at the opposite extremity of the board, preferably centered about the pencil or other marking medium.

The operator is merely required to trace 85 the contour of his drawing with the stylus or pointer 19 and the marking instrument 21 will reproduce a similar contour upon the adjacent sheet. It is obvious that the construction of the device is unusually simple while possessing many advantages over similar devices now in use.

100 It is to be understood that the form of my invention herewith shown and described is to be taken as the preferred example of the same, and that various changes in the shape, size, and arrangement of parts may be resorted to without departing from the spirit of the invention, or the scope of the subjoined claim.

Having thus described my invention, I 110 claim:

A pantograph apparatus comprising a board, a brace disposed transversely across

the board, securing devices carried by the board and spaced at equal distances from the brace and located between the edge of the brace and the end edge of the board, an arm connected with the securing devices and having an edge bearing against the adjacent edge of the brace, extension bars pivotally connected with the arm, a connecting bar pivotally connected with the free ends of the first mentioned bars, a cross arm

secured to the connecting bar at a point midway between the ends of the cross bar and at a point midway between the ends of the said arm, tracing arms pivotally connected with said cross arm and a brace bar pivotally connected at its end with the tracing arm at points between the ends thereof. 15

In testimony whereof, I have affixed my signature.

MAURICE M. ANDERSON.
